SHUTTLE BINDER AND SUPPORT

Filed Jan. 18, 1949

UNITED STATES PATENT OFFICE

2,525,129

SHUTTLE BINDER AND SUPPORT

Drew Wright Hageman, Mountain Lakes, N. J., assignor, by mesne assignments, to Steel and Alloy Tank Company, Newark, N. J., a corporation of New Jersey

Application January 18, 1949, Serial No. 71,430

8 Claims. (Cl. 139—185)

1

The present invention relates to improvements in shuttle binders for looms.

The usual binder for checking the shuttle and for controlling the protector motion, pivots about a pin or stud affixed to the lay or to the box bottom plate. The fit between the binder and the pivot pin or stud is close enough to limit pivotal movement of said binder in a plane perpendicular to the axis of said pin. As a result, unless the shuttle comes into the box at even keel, the inner side of the binder does not engage the corresponding side of the shuttle with a close surface contact fit. This causes uneven wear of the shuttle, binder and box parts and impairs shuttle checking action as the shuttle is being boxed.

If a resilient pivot mounting is provided for the binder, the binder may be displaced radially towards the axis of the pivot and this may cause the shuttle to be boxed out of alignment with the corresponding picker. Moreover, the lateral displacement of the binder permitted by such a resilient pivot mounting may affect adversely the accuracy and sensitivity of the protection motion.

One object of the present invention is to provide a new and improved pivot mounting for the binder, which permits the binder to tilt about its longitudinal axis to maintain continuous frictional surface contact between the binder and the shuttle as it is being boxed and which is not yieldable in a radial direction with respect to the axis of the pivot mounting, so that axial alignment of the shuttle with the corresponding picker and true shuttle flight is substantially maintained.

Various other objects of the invention are apparent from the following particular description and from an inspection of the accompanying drawings, in which:

Fig. 1 is a top plan view of a lay and shuttle box assembly shown at the instant the shuttle is being boxed;

Fig. 2 is a transverse section of the lay and shuttle box assembly taken on lines 2—2 of Fig. 1 and shown with the shuttle coming in at even keel; and

Fig. 3 is a transverse section of the lay and shuttle box assembly similar to that of Fig. 2 but showing the shuttle coming in slightly tipped about its longitudinal axis.

Referring to the drawings, the binder post mounting of the present invention is shown applied to a shuttle box 10 fastened to the lay 11, as for example, by bolts 12, and comprising a bottom plate 13, a front plate 14 with a top shuttle guide plate 15 secured thereto, and a rear or back plate

2

16 spaced from said front plate to receive the conventional shuttle 17 therebetween during shuttle boxing action.

The shuttle 17 is propelled by a picker stick 18 in any suitable manner. The bottom box plate 13 has a slot 20 for the passage of the picker stick 18.

The invention is not limited to any particular kind of picking mechanism or general shuttle box construction and that shown is for illustrative purposes only.

The rear of the shuttle box 10 has extending therethrough a shuttle binder 25 pivoted at one end 26 to the bottom box plate 13 by a pivot mounting 27 and engaging at its other free end the usual protector finger (not shown) for protector motion control. A spring (not shown) yieldingly holds the binder 25 inwardly towards the front box plate 14 to check the shuttle 17 as it moves into the box 10.

The binder 25 comprises an elongated bar 28 desirably of wood and desirably provided on its inner shuttle contacting side with a lining 30 of leather or similar flexible cushioning material cemented or otherwise secured thereto. At its pivoted end 26, the binder 25 has a hub 31 forming part of the pivot mounting 27, as will be described.

The binder pivot mounting 27 comprises a rigid pivot pin 32, desirably of metal, secured to the bottom box plate 13 by a clamping bolt or stud 33, which is anchored to said box plate, as will be described, and which passes through said pivot pin. The binder pivot mounting 27 also comprises a rigid bearing bushing or sleeve 34, desirably of metal or other suitable bearing material, lining the inside of the binder hub 31 and having rotative bearing engagement with the outer periphery of the pivot pin 32. The hub bushing 34 has a hole 35 presenting an inner convexly curved surface 36 in rocking engagement with the pivot pin 32, permitting said bushing 34 not only to rotate about the pivot axis of the binder mounting 27 but to tilt about an axis transverse to said pivot axis, as will be more fully described.

More specifically, the pivot pin 32 is an eccentric bushing designed to permit adjustments in the transverse position of the pivot axis of the binder mounting 27. The eccentric bushing has a cylindrical bearing shank 38 and an annular base flange 40 seated on the bottom box plate 13 and provided with a series of holes or sockets 41 around its periphery to receive a suitable wrench or other turning tool. The binder hub bushing 34 seats on the base flange 40 and engages the

cylindrical surface of the shank 38 of the eccentric bushing 32 with a rotatable rockable fit, as described.

The clamping bolt 33 is threaded at its lower end into a splined nut 45 locked to the bottom box plate 13 against rotation. At its upper end, the bolt 33 is provided with a head 46 fitted into a counterbore in the hole of the eccentric bushing 32 and provided with a socket 47 for receiving a wrench or other turning tool.

Normally, the bolt 33 is tightened to lock the eccentric bushing 32 in adjusted position against rotation. When it is desired to adjust the transverse position of the center axis of the bushing 32, the bolt head 46 is turned to turn the bolt 33 in the splined nut 45 and to loosen thereby the eccentric bushing 32. The bushing 32 can then be turned by inserting a wrench into a socket 41 of its base flange 40 and rotating thereby said bushing into the desired position. When the proper adjustment in the rotative position of the eccentric bushing 32 has been made, the bolt 33 may be turned to lock the parts in adjusted position.

The hole 35 of the hub bushing 34 tapers from opposite ends towards substantially the center to present the smooth rounded internal surface 36 convexly curved lengthwise of said bushing. The surface is curved substantially circularly in the radial planes of the axis of the hub bushing 34, so that said hub bushing constitutes substantially a solid of revolution generated by a segment of a circle rotating about an axis which is spaced from said segment, which is substantially parallel to the chord of said segment and which is located on the side of the arc of said segment opposite said chord. The radius of the arc is small enough to permit tilting of the binder 25 about its longitudinal axis through an angle sufficient to accommodate any keeling of the shuttle 17 normally encountered during shuttle boxing operations, but is large enough so that the spur of the shuttle 17 is maintained substantially in alignment with the corresponding picker.

In Fig. 2, the shuttle 17 is shown coming into the box 10 at even keel. In this position, the inner leather lined surface of the binder 25 is in close, continuous, frictional surface contact with the corresponding side of the shuttle 17. In Fig. 3, the shuttle 17 is shown coming into the box 10, slightly tilted about its longitudinal axis. In this position, the binder 25, through the tilting compensating movement of its hub bushing 34 about the pivot bushing 32, has been tilted about its longitudinal axis in position corresponding to the tilted position of the shuttle 17 and into close, continuous, frictional surface contact with the side of said shuttle. Even wear of the shuttle contacting parts is thereby assured and effective shuttle checking action is by that means maintained at all times.

While the invention has been described with particular reference to a specific embodiment, it is to be understood that it is not limited thereto but is to be construed broadly and strictly solely by the scope of the appended claims.

What is claimed is:

1. In a shuttle box for a loom, a bottom box plate, a binder, and means for mounting said binder for pivotal movement with respect to said bottom box plate and including a rigid pivot pin member supported in fixed position with respect to said bottom box plate, and a rigid bearing member secured to said binder near one end and

embracing said pivot pin member with a rotative bearing fit, one of said members presenting to the other member a surface curving along said pivot pin member to permit limited rocking movement of said bearing member about an axis transverse to the axis of said pivot pin member and to permit thereby said binder to tilt about its longitudinal axis to accommodate for any tilt in the shuttle about its longitudinal axis as it is being boxed.

2. In a shuttle box for a loom, a binder and a mounting therefor, comprising a rigid pivot pin member fixed with respect to said binder, and a rigid bearing sleeve member secured to one end of said binder and embracing said pin member with a rotative bearing fit, one of said members being convexly curved lengthwise to permit said bearing sleeve member to rock along said pivot pin member about an axis transverse to the axis of said pivot pin member and to permit thereby said binder to tilt about its longitudinal axis to accommodate for any tip in the shuttle about its longitudinal axis as it is being boxed.

3. In a shuttle box for a loom, the combination as described in claim 2, said pivot pin member presenting a cylindrical bearing surface to said bearing sleeve member, said bearing sleeve member being convexly curved lengthwise around its entire internal periphery.

4. In a shuttle box for a loom, the combination as described in claim 2, said pivot pin member presenting a cylindrical bearing surface to said bearing sleeve member, said bearing sleeve member having an internal surface convexly curved substantially circular in the radial planes of the axis of said sleeve member.

5. In a shuttle box for a loom, the combination as described in claim 2, said pivot pin member constituting an eccentric, said combination comprising clamping means supporting said pivot pin member for rotative adjusting movement.

6. In a shuttle box for a loom, the combination as described in claim 2, said pivot pin member constituting an eccentric bushing, said combination comprising a clamping screw adapted to support said pivot pin member and passing through said pivot pin member, said screw being adapted to be loosened to permit rotational adjustment of said pivot pin member about said screw and being adapted to be tightened to lock said pivot pin member in adjusted rotative position.

7. In a shuttle box for a loom, a bottom box plate, a binder having a hub at one end, and means for adjustably mounting said binder for pivotal movement with respect to said bottom box plate and including a stud secured to said box plate, a rigid cylindrical eccentric pivot bushing embracing said stud and adapted to be rotated for adjustment when said stud is loosened and to be clamped in adjusted position when said stud is tightened, and a rigid bearing bushing for said binder hub embracing said pivot bushing with a rotative bearing fit, said bearing bushing being convexly curved lengthwise around its inner periphery to permit said bearing bushing to rock along said pivot bushing about an axis transverse to the center axis of said pivot bushing, and to permit thereby said binder to tilt about its longitudinal axis to accommodate for any tip in the shuttle about its longitudinal axis as it is being boxed.

8. In a shuttle box for a loom, a bottom box plate, a binder having a hub at one end, and

means for adjustably mounting said binder for pivotal movement with respect to said bottom box plate and including a rigid cylindrical eccentric pivot bushing seated on said box plate and having an annular base flange with sockets to receive a turning tool, a clamping bolt passing eccentrically through said bushing, a nut secured to said bottom box plate against rotation and threaded on to the lower end of said bolt, the upper end of said bolt having a head bearing against the upper end of said bushing, said bolt being adapted to be loosened to permit rotative adjustment of said bushing thereabout and being adapted to be tightened to lock said bushing in adjusted position, and a rigid bearing bushing for said binder hub embracing said pivot bushing with a rotative bearing fit, said bearing bushing being convexly curved lengthwise around its inner periphery to permit said bearing bushing to rock along said

pivot bushing about an axis transverse to the center axis of said pivot bushing, and to permit thereby said binder to tilt about its longitudinal axis to accommodate for any tip in the shuttle along its longitudinal axis as it is being boxed.
